HORACE M. MARSHALL, OF VICKSBURG, MISSISSIPPI.

SHEET PILING.

Application filed December 11, 1923. Serial No. 680,056.

This invention relates to sheet piling, and more particularly to an improved construction of wooden piling and the method of making the same.

5 Wooden sheet piling, consisting of a series of vertical sections, with their edges interlocked, is well known, and many types of interlocking tongues and grooves have been proposed. The sections are often built up 10 from structural units or elements, so formed and assembled as to provide a tongue projecting from one edge, and a groove or recess in the opposite edge, the tongues and grooves of adjacent sections being arranged 15 to interlock so as to prevent separation of the sections.

The interlocking tongues and grooves, above mentioned, have heretofore been formed either by nailing or bolting separately formed strips to the sides or edges of the structural units, or else by shaping such units in a wood working machine, such as a planer, with a cutter specially shaped to produce the particular outline of tongue 25 or groove desired. The first of these methods is objectionable because of the relatively large amount of labor required to assemble and nail together the various strips and units, and the second method is objectionable because of the great waste of material which it involves, and also, on account of the cost of machining or planing the units.

One object of the present invention is to provide an improved sheet piling section 35 made up of structural units, provided with integrally formed tongues, and having all of the advantages of the planed or machine cut units, but with substantially no waste of material and with much lower cost of manufacture. This end I achieve by sawing out 40 the structural units from a rectangular stick of timber in a novel manner, as hereinafter described.

Another object is to provide means, in 45 connection with such an improved sheet piling section, whereby a jet pipe may be inserted at a point between adjacent sections, to aid in sinking the sections.

In order that the invention may be readily 50 understood, reference is had to the accompanying drawing, forming part of this specification, and in which:—

Fig. 1 is a perspective view of one end of 55 a rectangular stick of timber, having indicated thereon, in dotted lines, my novel method of sawing;

Figs. 2, 3, 4 and 5 are similar perspective views, showing the shape of the different pieces or elements severed from the stick of timber by means of the saw cuts, shown in Fig. 1;

Fig. 6 is a transverse section through two interlocked sections of my improved piling, showing the method of building up and assembling the same by means of structural units, such as illustrated in Figs. 2, 3 and 4, and also showing the location of the jet pipe;

Fig. 7 is a series of views in end elevation, conventionally showing the successive steps 70 employed in cutting up a stick of timber, such as shown in Fig. 1;

Fig. 8 is a view similar to Fig. 1, showing how structural elements or units can be made 75 from a rectangular stick of timber, by means of a lesser number of saw cuts to produce the elements shown in Figs. 2, 3, 4 and 5;

Figs. 9 and 10 are views similar to Figs. 2 and 3, showing the structural elements so produced; and

Fig. 11 is a cross section through two interlocked sections of piling, showing a somewhat different method of building up and assembling such sections from the same type of structural elements.

Referring to the drawings in detail, and particularly to Figs. 1 to 7 thereof, my novel method of sawing up a rectangular stick to form structural elements will first be described.

The rectangular stick, which I preferably employ, has two relatively narrow and two relatively wide faces, and is designated, in its entirety, by the reference numeral *x*. This stick of timber is divided into the structural units hereinafter described, by means of saw cuts running longitudinally of the stick, which cuts may be made by means of an ordinary circular saw.

I first make a cut, as indicated by the reference numeral 1, at A, in Figure 7, such cut extending from one of the narrow faces of the stick *x* toward the other narrow face, parallel with the wide faces. This cut is spaced a distance from one of the wide faces, equal to the thickness of the structural unit desired, and preferably equal to one-third the width of the narrow faces. This saw cut 1 terminates at a point spaced the same distance from the opposite narrow face that the cut is spaced from the adjacent wide face.

I next make a saw cut extending into the stick from the opposite narrow face, as indicated by the numeral 2, at B, in Figure 7. This second cut is spaced an equal distance 5 from the first cut and from the adjacent flat face of the stick, so that cuts 1 and 2 divide the stick into three sections of equal thickness. The second cut terminates at a point spaced from the first narrow face, a 10 distance equal to the spacing of the first cut from the opposite narrow face, so that the stick, having the two cuts, as shown at B in Figure 7, is symmetrical.

I next make a third saw cut, as indicated 15 by the reference numeral 3, at C, in Figure 7, this third saw cut extending from the end of the first saw cut, out through the wide face of the stick, adjacent the second saw cut, such third saw cut being parallel 20 with the narrow face of the stick, and crossing the second saw cut.

As a result of this third saw cut, the stick is severed into three pieces, namely, an L-shaped piece, as shown in Figure 2, a strip 25 substantially square in cross section, designated by the reference numeral *d*, at C, in Figure 7, and shown in perspective in Figure 5, and a rectangular piece such as shown at D in Figure 7, smaller than the original 30 stick *w*. This rectangular piece D already has the saw cut 2 extending through the center thereof, to a point adjacent one narrow face.

The last step of my novel method of sawing 35 consists in making a fourth saw cut 4 from one wide face of the piece D, to the extremity of the cut 2, in a direction parallel with the narrow faces of the piece. This divides the piece D, as shown in Figure 7, 40 into two separate elements, namely, a flat board or plank *b*, and a second L-shaped piece *c*, smaller than the first.

These various elements are clearly shown 45 in Figs. 2, 3, 4 and 5, in which the first L-shaped piece is indicated by the reference character *a*, and comprises a web or body and an integrally formed tongue or flange *a'*. The flat board or plank is shown at *b* in Figure 3, and the second L-shaped element is shown at *c* in Figure 4, and, like the 50 element *a*, comprises a flat web or body and an integrally formed tongue or flange *c'*. The small strip of square cross section is shown at *d* in Figure 5, and represents the portion cut from the two L-shaped members 55 by means of the saw cuts 2 and 3, at the point where they cross.

In forming a section of sheet piling from 60 structural units of the nature above described, and shown in Figs. 2, 3 and 4, I first take two of the smaller L-shaped pieces *c* and assemble them back to back, with their flanges *c'* projecting in opposite directions, as shown in Figure 6. I then place at each 65 side of these assembled elements, one of the

flat boards *b*, these boards being offset relative to the elements *c*, so that a space *j* is provided between one edge of these boards and the flange *c'*, and the opposite edge of the boards projects beyond the adjacent edge 70 of the elements *c*, so as to form a groove or space *k*. Outside of the boards *b*, I finally place two of the larger L-shaped elements *a*, shown in Figure 2, with their flanges *a'* 75 projecting toward each other and with their opposite edges flush with the adjacent edges of the boards *b*. The relative sizes of these boards and the L-shaped elements *a* is such that when assembled as described, a space or groove is provided between each flange 80 *a'*, and the adjacent edge of the board *b*, as clearly shown at *h* in Figure 6.

When interlocking a plurality of such sections to form sheet piling, the two opposed spaces *h*, just described, formed by the 85 tongues *a'*, constitute grooves in which the two outturned flanges or tongues *c'*, of the adjacent section, fit. This is obvious from an inspection of Figure 6. From this figure, it will also be seen that there is a channel 90 or groove *k* at one edge of each section, formed between the edges of the boards *b* where they project beyond the edge of the pair of units *c*, and that this channel is not occupied by any part of the tongue of an 95 adjacent section. This channel thus provides an ideal passage or space for the insertion of a jet pipe, as indicated at *z*.

In erecting my improved piling, one section is first driven down, in the usual manner. A jet pipe *z* may then be inserted in the space or channel *k*, and water under pressure supplied thereto. The jet issuing from the lower end of the pipe serves to wash away the dirt from the adjacent groove 105 *h* of the driven pile section, and clean it out, so that the tongue or flange *c'* of the section to be driven may readily enter said groove, and effectively interlock the sections. As the second section is forced downward into 110 position, the water from the jet loosens up and softens the earth immediately adjacent the driven section, and this causes the pile section being driven to be crowded against the one already in place, by reason of the fact that the earth at the outside edge of the section being driven, not being subjected to the action of the jet, is firmer than that at the inner edge, where the jet is operating. In this way, any tendency of the successive 115 sections to separate from the preceding ones, is effectively overcome.

From the above description, it will be seen that by means of a few simple sawing operations, I am enabled to produce, from an ordinary rectangular stick of timber, substantially without waste, a plurality of structural elements, all of which can be employed, just as they come from the saw, for building up pile sections with effectively 120 125 130

interlocking tongue and groove joints. It will be particularly noted that the flanges a' and c' , forming the interlocking tongues, constitute integral parts of the L-shaped members produced by my novel method of sawing. It will thus be seen that the necessity of nailing on special strips to form interlocking tongues is avoided and also that no planing or machining whatever is required. All of the elements or structural units sawed from the stick x are utilized, with the possible exception of the small strip, d , and even this, if desired, may be employed to partially fill the space or passage k . Thus, all waste of material is eliminated, and I am enabled to secure a maximum amount of piling from a given quantity of timber. Moreover, my improved L-shaped members or units have comparatively wide flanges a' and c' , which provide interlocking tongues with unusually wide and strong engaging surfaces, thus resulting in an exceptionally rigid and durable construction.

I may, if desired, cup up the original stock of timber in a manner similar to that indicated at D in Figure 7. This is shown in Figures 8, 9 and 10, in which y designates an original rectangular stick of timber, and the dotted lines 1 and 2 indicate intersecting saw cuts by means of which the stick of timber is divided. It will be seen that this method of cutting results in the production of an L-shaped member e , having an integral flange e' , similar to the element shown in Figure 2, and a flat element or board f .

In some cases, where a lighter construction is permissible, I may form my improved sections of piling from only five structural elements instead of six, as shown in Figure 6. The method of assembling five structural elements comprising L-shaped pieces and flat boards of the character described, to form a section having interlocking tongues and grooves, is illustrated in Figure 11. By reference to this figure, it will be seen that I take a flat board, such as f , and place it between two L-shaped units, such as e , with the flanges or tongues e' at opposite sides of the board, and projecting in opposite directions. Each L-shaped unit is offset, relative to the central board, so as to provide a groove or channel i between each flange e' and the adjacent edge of the board f . To the outside of each L-shaped member thus assembled, I secure a flat board g , wider than the board f , and so disposed that one edge is flush with the outer edge of the flange e' , and the other edge is substantially in the same plane as the adjacent edge of the board f .

From an inspection of Figure 11, it will be seen that when the two sections are assembled, one flange or tongue e' of each section enters the groove i of the other section, the two tongues e' thus being in engagement

with each other, and the sections being thereby securely interlocked. The projecting edges of the boards g constitute the outer walls of the groove and prevent the separation of the tongues e' , as is obvious.

By further reference to Figure 11, it will be seen that spaces or passages o are formed, adjacent the end of each L-shaped element e , between the boards f and g . These spaces may be used to receive a jet pipe, as shown in Figure 6, or, if desired, may be filled with cement, as indicated in Figure 11. In Figure 6 I have shown the structural units making up my improved section as held together by means of bolts m , and in Figure 11, I have shown the units as held together by means of nails n . Either of these, or any other known method of fastening, may of course be employed in either type of construction.

It will thus be seen that I have devised a novel method of sawing up ordinary timber into structural units, which units may be utilized in the construction of improved piling sections, without waste and with a minimum amount of labor, and which units comprise L-shaped elements having integrally formed webs and flanges, the flanges serving as interlocking tongues, and the sections having spaces to receive jet pipes, and it is thought that the many advantages of my invention will be readily appreciated, without further discussion.

What I claim is:—

1. A wooden sheet piling comprising a plurality of sections, each section being built up wholly by flat boards and wooden pieces L-shaped in cross-section, each of said pieces consisting only of a web and a flange arranged at right angles and integrally united, the length of the flange of each piece being substantially equal to the thickness of said flat boards and to the thickness of the web, said elements being assembled and secured together with a flat board interposed between two reversely arranged opposed L-shaped pieces, the edges of said board being spaced from the flanges of said L-shaped pieces a distance equal to the thickness of said flanges, whereby each section is provided at its edges with a tongue and groove, the grooves and tongues of adjacent sections being constructed to interlock.

2. A wooden sheet piling consisting of a plurality of sections, each section being built up wholly of flat boards and pieces L-shaped in cross-section, each piece being formed by a web and a flange arranged at right angles, and integrally united, the lengths of the flange of each piece being substantially equal to the thickness of the web and of said flat boards, and each section comprising at least one pair of such pieces and at least two flat boards, said L-shaped pieces and boards being rigidly secured together in assembled

relation in such manner that one of the flat boards is interposed between the pair of L-shaped pieces, the latter being reversely disposed with the flange of each directed toward the plane of the web of the other, and the edges of said board being spaced from said flanges a distance equal to their thickness, whereby each section is provided at its edges with a tongue and groove, the 10 grooves and tongues of adjacent sections being constructed to interlock.

3. In a wooden sheet piling, a section having an interlocking tongue and groove at each edge thereof, said section including a 15 pair of integrally formed wooden pieces, L-shaped in cross-section, each consisting of a web and flange only, said L-shaped pieces being assembled with their flanges extending in opposite direction and their webs 20 parallel, and with a flat board interposed between their webs, the length of the flange of each piece being substantially equal to

the thickness of the web and of said flat board, the width of said board being no greater than the length of said webs, and its 25 edges being spaced from said flanges a distance equal to the thickness of the flanges.

4. In a wooden sheet piling, a section having an interlocking tongue and groove at each edge thereof, said section being made 30 up of two pairs of integrally formed wooden pieces, L-shaped in cross-section, each consisting of a web and flange only, one pair of said L-shaped pieces being assembled back to back with their flanges extending in 35 opposite directions, and the other pair being disposed with their flanges extending toward each other, and with a flat board interposed between the webs of each of said second pair of pieces and one of the first 40 named pair.

In testimony whereof I affix my signature.

HORACE M. MARSHALL.
